UNITED STATES PATENT OFFICE.

DANIEL H. STRAYER, OF LOS ANGELES, CALIFORNIA.

COMBINED DOOR CHECK AND BUFFER.

1,415,493.

Specification of Letters Patent.

Patented May 9, 1922.

Application filed June 7, 1921. Serial No. 475,575.

To all whom it may concern:

Be it known that I, DANIEL H. STRAYER, a citizen of the United States, residing in Los Angeles, in the county of Los Angeles and State of California, have invented certain new and useful Improvements in Combined Door Checks and Buffers, for which the following is a full and complete specification, reference being had to the accompanying drawings.

The present invention relates to a device for preventing the door knob of a door from coming into contact with the wall when the door is open and for preventing the slamming of the door when the same is closed.

It is an object of the present invention to provide a device of this character which will be cheap to manufacture and which may be readily attached to any door, case-
ment window or similar structure.

It is a further object to provide a structure of the type described which is manufactured of pressed or stamped metal.

In order to more fully disclose the present invention reference is had to the accompanying drawings, in which—

Fig. 1 shows a preferred embodiment of the same, and

Figs. 2, 3 and 4 show the structure suitably mounted upon a door.

The structure as shown in Fig. 1 comprises a stamped metal piece having a portion 1 adapted to be pivotally mounted on the edge of a door by means of a screw passing through the hole 1'. The member 1 carries at one extremity an elongated portion 2 which is bent at right angles to the portion 1 at 3. A roller 4 of rubber or other yieldable or resilient material is mounted

upon the opposite extremity of the member 1 by means of a pivot or stud 5. The elongated portion 2 has mounted at its inner end a check buffer of resilient material 6, and carries at its outer extremity a second buffer of resilient material 7. As shown the buffer 7 is held in place by two ears of the stamp metal piece which are bent to form a retaining cup, although other forms of retaining means may be used. A

notch 8 is also provided near the extremity of the elongated portion 2 which notch is adapted to cooperate with a hook or detent member 9 for holding the door open as shown in Fig. 4.

As shown in Figs. 2 and 3, the device is

pivottally attached to the edge of a door, swinging window or other equivalent structure, by means of a screw 10 passing through the hole 1'. A washer may be provided, if desired, between the portion 1 and the door. 60 The point of attachment of the screw is so selected with reference to the edge of the door and the size of member 1 that when the door is opened, the weight of the elongated portion 2 causes it to fall and to assume a normal position at a right angle to the plane of the door as shown in Figs. 3 and 4. While the weight of the elongated portion 2 is sufficient in ordinary circumstances to cause it to assume this position, 70 resilient means may be provided to normally urge it into this position, if desired. If the door is now swung open the resilient buffer 7 will come in contact with the base-board, the elongated portion 2 being of such 75 length as to prevent the door knob from coming into contact with the plaster.

When the door is closed the roller 4 coming in contact with the door jamb, tilts or rocks the member 1 about the screw 10 into 80 the position shown in Fig. 2, causing the check buffer 6 to come in contact with the side of the door. The resilient buffer 4 contacting with the jamb and the resilient buffer 6 contacting with the door cooperate to 85 form a resilient check or silencer thereby permitting the door to be closed without undue noise or slam. If desired, the check buffer 6 may be omitted and buffer 7 be designed to function also as the check buffer 90 when the door is closed. Both buffers 6 and 7 and the roller 4 are fitted so as to be easily renewed when worn.

The notch 8 is provided near the extremity of the elongated portion 2 for cooperation 95 with a hook or detent member 9 which is mounted on the base-board or wall in such manner as to hold the door open as shown in Fig. 4. This feature in combination with the door check function provided for by the 100 resilient buffer 6 renders the invention especially advantageous in the use of screen doors which are normally held closed by means of a spring.

The device is also well adapted for use on 105 bath room doors where there is a tiled wainscoting upon which it is difficult to mount the ordinary type of door buffer.

While the structure is described as being constructed of stamped metal, it is obvious 110

that the same may be cast or die formed. The stamp metal construction, however, is advantageous in that the device may be stamped complete in one piece and subsequently bent in either direction at the part 5 to fit either a right or left hand door.

The device can be made in any style or finish to correspond with the other hardware on the door.

10 Further modifications may be made in the structure without departing from the spirit of the invention as set forth in the appended claims.

What I claim is:

15 1. A structure of the class described comprising a member adapted to be pivotally mounted on the edge of a door and having an elongated portion normally projecting outwardly from the plane of the door, and 20 means carried by said member contacting with the door jamb when the door is closed for pivoting said elongated portion from its normal position.

25 2. A structure of the class described comprising a member adapted to be pivotally mounted on the edge of a door and having an elongated portion normally projecting outwardly from the plane of the door and carrying a resilient buffer on its extremity, 30 and means carried by said member contacting with the door jamb when the door is closed for pivoting said member from its normal position.

35 3. A structure of the class described comprising a member adapted to be pivotally mounted on the edge of a door and having an elongated portion normally projecting outwardly from the plane of the door, and a resilient roller carried by said member 40 contacting with the door jamb when the

door is closed for pivoting said elongated portion from its normal position.

4. A structure of the class described comprising a member adapted to be pivotally mounted on the edge of a door and having an 45 elongated portion normally projecting outwardly from the plane of the door, means carried by said member contacting with the door jamb when the door is closed for pivoting said elongated portion from its normal position, and means carried by said elongated portion for yieldingly contacting with the side of the door when said elongated portion is pivoted from its normal position during 50 the door closing operation.

5. A structure of the class described comprising a member of stamped metal having a portion adapted to be pivotally mounted on the edge of a door, an elongated portion 60 at right angles to said first named portion and normally projecting outwardly from the plane of the door, and means carried by said first named portion contacting with the door jamb during the door closing operation 65 for pivoting said elongated portion from its normal position.

6. A structure of the class described comprising a member adapted to be pivotally mounted on the edge of a door and having an elongated portion normally projecting outwardly from the plane of the door, catch 70 engaging means carried by said elongated portion near its outer extremity and means carried by said member contracting with the door jamb during the door closing operation 75 for pivoting said elongated portion from its normal position.

In testimony whereof, I have hereunto affixed my signature.

DANIEL H. STRAYER
